LID CONSTRUCTION

Adrianus A. Kooyman, Chicago, Ill., assignor to
International Harvester Company, a corpora-
tion of New Jersey

Substituted for abandoned application Serial No.
218,160, July 8, 1938. This application Febru-
ary 10, 1941, Serial No. 378,420.

4 Claims. (Cl. 292—159)

This application is filed to take the place of the application of Adrianus A. Kooyman, Serial Number 218,160, filed July 8, 1938, which became abandoned.

This invention relates to a lid construction. More specifically, it relates to an arrangement applicable to a pair of lids of a refrigerator or the like for locking the one lid to prevent its being opened while the other is open.

It is often desirable, in cases where there are separate lids for adjacent compartments, that the one compartment be closed while the other is open. In refrigerator construction, for example, where there are adjacent compartments for food and refrigerant, it is extremely desirable that the lid to only one compartment be allowed to open at one time. Constructions have already been devised for locking one lid while an adjacent lid is open, but they have been complicated and generally unsatisfactory.

An object of the present invention is to provide a construction by which the opening of one lid of a pair of adjacent lids prevents the opening of the other lid.

Another object is the provision of a lid construction in which one lid is positively locked against opening while the other lid is open.

A further object is to provide in connection with a lid construction an arrangement for releasing the counterbalancing action of a spring intended to hold open a lid.

Still another object is the provision of a release mechanism for a counterbalancing spring in connection with a double lid construction.

A further object is to provide a lid construction in which the opening of one lid prevents the opening of an adjacent lid, there being provided release mechanisms for counterbalancing springs associated with the lids.

Other objects will appear from the disclosure.

According to the present invention, a pair of containers, one within the other, provide adjacent compartments suitable for food and refrigerant. Lids for the compartments are pivotally attached on aligned axes to extend in the same direction from the axes in closed position. Arcuate straps extend from the inner sides of lids and are slotted adjacent the lids. A pin extends between the straps with its ends partially in the slots. When the one lid is opened, the end of the pin moves out of the slot and the pin is moved longitudinally by contact with the strap further into the slot in the other strap, so that movement of the latter strap to release the pin from engagement with the slot is impossible and the lid is

locked in closed position against the compartment. Counterbalancing springs are connected to the lids and containers, so as to hold the lids in open position. A mechanism is provided for releasing the action of the counterbalancing springs when the doors are moved nearly into closed position.

In the drawings:

Figure 1 is a sectional view taken along the line 1—1 of Figure 3, but with the lids closed;

Figure 2 is a similar section with one lid in open position;

Figure 3 is a section taken along the line 3—3 of Figure 1, but with the same lid partially open;

Figure 4 shows in detail a locking pin;

Figure 5 shows a sleeve for the locking pin;

Figure 6 shows a bell-crank member for releasing a counterbalancing spring;

Figure 7 is a detail, showing a member on which the locking pin is mounted;

Figure 8 is a perspective view, showing how the locking pin is mounted; and,

Figure 9 is a detail, showing a connecting piece for a counterbalancing spring.

A dry tank 10 for food is mounted within a refrigerant tank 11 in a manner not completely shown, since it forms no part of the present invention. In any event, the tanks are so arranged as to form separate compartments for food and refrigerant. A lid 13 covers the food compartment, and a lid 14, the refrigerant compartment. The lids are hinged on aligned axes, as at 15. Secured to the under side of the lids 13 and 14, respectively, are arcuate straps 17 and 18, the centers of which fall on the aligned pivot axes 15 of the lids. Each strap is slotted near its point of attachment to the lid, as at 19, with a sloping groove 20 extending from the slot on the surface facing the other strap.

The dry tank 10 has a flange 21, by means of which the tank is supported at one side on a pair of angle irons 22 and 23, having end portions 22' and 23' resting on the refrigerant tank 11. As shown in Figure 7 for the angle iron 22, the angle iron 23 being similarly formed, there is a threaded opening 24 and an elongated slot 25 with a circular portion 26 at one end. Secured opposite this circular portion to angle iron 23 is a U-shaped member 28 with a registering opening and a slot 29 receiving the arcuate strap 18, as shown in Figure 8. A short tubular section 30 is secured in the opening 26 of the angle members 22 and 23 and the registering opening of the U-shaped member 28, and is almost as long as the distance between the straps 17 and 18,

45

50

55

There is an elongated opening 31 in the tubular section 30 nearer the end which is opposite the strap 17 (see Figures 3 and 5). A locking pin 33 is positioned within the tubular section 30 and has an opening 34 opposite the opening 31 in the tubular section. There are reduced ends 35 and 36 on the locking pin 33, which extend partly through the slots 19 in the arcuate straps 17 and 18 when the lids are both in closed position. A spring member 38 extends into the opening 34 in the pin 33 and has an eye portion 39, through which a bolt 40 extends and is secured to the angle members 22 and 23, securing the spring member thereto. The spring member tends to retain the locking pin 33 in a central position between the straps 17 and 18, and yet allows it some movement along its length into and out of the slots 19 in the arcuate members 17 and 18.

Clips 41 are welded to the ends of the members 17 and 18 and retain, by means of pins 42 passing through holes 42' in legs 43, bolts 44 fastened to one end of counterbalancing springs 45. Bolts 46 connect the other end of the springs and brackets 47, secured to the angle members 22 and 23. The arrangement is such that either lid tends to stay in the open position of Figure 2, for in this position the clips 43 are closest to the brackets 47. When the lid is shut, the spring 45 is caused to elongate and resist the movement to closed position. In order that the counterbalancing action may be released in closed position, bell-crank member 50, shown in detail in Figure 6, and nut 51 on bolt 44 are provided. The bell-crank member 50 is pivoted on the angle members 22 and 23, as at 52. As the lid 14 moves to closed position, the end of the arcuate strap 18 strikes an end portion 54 of the bell-crank member 50, which is spaced a considerable distance from the pivot at 52. The bolt 44 passes between legs 55 with the nut 51 resting against the legs when closed position has been reached. In this position, the distance between the contact of the nut 51 and legs 55 and pivot point 52 is small in comparison with the distance between pivot point 52 and the point of contact of strap 18 on end portion 54 of the bell-crank member. Consequently, in the closed position or in the approach to closed position, the effective lever arm at which the spring 45 acts is small in comparison with the lever arm on which pressure applied to the cover acts, and the ability of the spring to resist closing force to the cover is considerably reduced. The mechanical advantage of the lid in respect to the spring is considerable.

When the lids are in closed position, the locking pin 33 occupies a mid-position between the straps 17 and 18 because of the action of the spring 38, with the ends 35 and 36 extending through the openings 19 in the straps 17 and 18 to a point opposite the sloping grooves 20. When lid 14, for example, as shown in Figure 3, is raised, the reduced end 36 of the pin 33 is able to slide out of the holes 19 of the strap 18 by passing along sloping groove 20. However, as this happens, the locking pin 33 is moved longitudinally farther into the opening 19 of strap 17 beyond the groove 20. If an attempt is now made to raise lid 13, the end portion 35 of pin 33 is not in a position to slide out of hole 19 of strap 17 by passing over sloping portion 20, and consequently strap 17 and lid 13 are locked against movement. If now lid 14 is lowered to closed position, end portion 36 of locking pin 33 moves back into hole 19 of strap 18, and end portion 35, partially out of hole 19 of strap 17. Now, 75

lid 13 may be raised, since end portion 35 of pin 33 is in a position to slide out of hole 19 along sloping groove 20. When this happens, locking pin 33 is moved far enough into strap 18 to lock it and lid 14 against movement.

It may be considered that the sloping groove 20 adjacent the hole 19 in one strap 18 constitutes means for displacing the end of the pin 33 in the hole to bring the other end of the pin into locked engagement with the hole 19 in the other arcuate strap 18.

In the open position of lid 14 of Figure 2, clip 41 contacts U-shaped member 28 and lid 14 rests against a stop 57. Thus, the opening of the lid is limited. A similar stop for limiting the movement of lid 13 is also provided.

It will be seen from the foregoing description that a novel structure has been provided in which one lid of a pair of lids is locked in closed position, while the other lid is open, and the counterbalancing action of springs on the lids is reduced as the lids are closed. The invention has been shown in connection with a refrigerator, but it is to be understood that the invention is applicable wherever lids or closures are used.

The invention is to be limited only to the terms of the appended claims.

What is claimed is:

1. In a lock for use with a container having a pair of lids positioned in side-by-side relation and extending in the same direction from aligned pivot axes on the container, a pair of arcuate members extending from the under side of the lids with their centers of curvature on the aligned pivot axes of the lids and having aligned holes in their closed position, a pin extending between the arcuate members with its ends extending partially through the holes in the members, and means supporting the pin and tending to maintain it in a mid-position between the arcuate members, each arcuate member having adjacent the hole therein means for displacing the end of the pin in the hole to bring the other end of the pin into locked engagement with the hole in the other arcuate member.

2. In a lock for use with a container having a pair of lids positioned in side-by-side relation and extending in the same direction from aligned pivot axes on the container, a pair of arcuate members extending from the under side of the lids on centers of curvature coinciding with the pivot axes of the lids regardless of the position of the lids and having aligned holes in closed position and shallow sloping grooves extending from the holes on the surfaces toward one another in a direction away from the lids, a pin extending between the lids with its ends extending partially through the holes in the arcuate members in the closed position of the lids, and means supporting the pin and tending to hold it in a mid-position between the arcuate members.

3. In a lock for use with a container having a pair of lids hinged on the container on aligned axes and extending in the same direction from the axes in closed position, a pair of arcuate straps extending inwardly from the lids with centers of curvature along the aligned hinge axes and having slots adjacent the lids, a pin extending between the straps with its ends partially extending through the slots in the straps, means connecting the container and the pin for maintaining the pin in a central position with respect to the straps, and a sleeve surrounding the pin and extending between the straps, each arcuate member having adjacent the slot therein means

for displacing the end of the pin in the slot to bring the other end of the pin into locked engagement with the slot in the other arcuate member.

4. In a lock for use with a container having a pair of lids positioned in side-by-side relation and pivoted on the container, a pair of rigid members extending from the lids into the containers and having aligned pin-receiving portions in the closed position of the lids, a pin extending between the 10

members with its ends in engagement with the pin-receiving portions on the members, and means supporting the pin and tending to maintain it in a mid-position between the members, each member having adjacent the pin-receiving portion therein means for displacing the end of the pin from the pin-receiving portion to bring the other end of the pin into locked engagement with the pin-receiving portion on the other member.

ADRIANUS A. KOOYMAN.
